UNITED STATES PATENT OFFICE

EDWARD A. ROCKWELL, OF NEW YORK, N. Y., ASSIGNOR TO STEWART-WARNEE CORPORATION, OF CHICAGO, ILLINOIS, A CORPORATION OF VIRGINIA

FUEL FEEDING APPARATUS OPERATED BY PRESSURE

Original application filed August 2, 1923, Serial No. 655,236. Divided and this application filed March 3, 1926. Serial No. 92,027. Renewed December 3, 1928.

This application is a division of my application #655,236, filed August 2, 1923, Patent No. 1,725,210, August 20, 1929, for covering one of the two forms of construction shown in 5 that application to the other of which the specific claims of that application are directed.

The purpose of this invention is to provide an apparatus for feeding fuel to internal 10 combustion engines with the aid of pressure and specifically by taking advantage of the alternation of super-atmospheric and sub-atmospheric pressure; that is, of pressure and suction as properly referred to; and the 15 specific construction herein shown has the specific purpose of affording continuous feed to the carburetor, as distinguished from the intermittent feed afforded by the modification to which the specific claims of the parent 20 application are directed. It consists in the elements and features of construction shown and described as indicated in the claims.

In the drawings:

Figure 1 is an elevation of an engine 25 equipped with an apparatus embodying the present invention.

Figure 2 is a vertical section at the line 2—2 on Figure 5 of a container in the apparatus shown in Figure 1 from which the fuel is fed 30 by pressure to the carburetor.

Figure 3 is a partly sectional side elevation of the container shown in Figure 2, section being made of certain parts at the line 3—3 of Figure 5.

Figure 4 is a vertical section of a controlling and pressure-limiting device located in the connection between the engine cylinder and the container shown in Figures 2 and 3.

Fig. 5 is a top plan view of the device shown by Figs. 2 and 3.

In the drawings I have shown an automobile engine which comprises a plurality of cylinders, 2, having pet cocks, 3, and spark plugs, 4, therein. The engine is shown as 45 having the usual intake manifold, 5, carburetor, 6, fan, 7, crank case, 8, gear case, 9, and transmission shaft, 10.

In one of the cylinders instead of a pet cock means is provided for communicating to the fuel feeding system pressure of the

cylinder varying from high super-atmospheric in the compression stroke, to sub-atmospheric in the suction stroke. This means comprises as shown in Figure 4 a pressure-controlling and limiting device indicated as 15 to its entirety by the numeral 80. It consists of a tubular portion, 81, arranged to be screwed directly into the fitting, 11, having for that purpose a hexagonal portion, 82, adapted to receive a wrench. The tubular portion, 81, has at its upper end a restriction, 83, for limiting the flow of gases from the engine cylinder through the device. At this point in the length of the part, 81, it has an exterior screw thread, 84, for screwing into a housing, 85, having an enlarged valve chamber, 86. Within the chamber, 86, there is a disk-shaped valve, 87, having an annular seating area, 88, at its upper edge which is flanged upwardly for that purpose. This 20 valve member rests downwardly upon the upper end of the part, 81, which at said upper end is recessed around the restricted port, 83, to form an annular flange which is notched to form projections, 89, upon which the valve, 87, is normally lodged by gravity,—not for seating as a valve; but on the contrary leaving ample clearance for the pressure fluid 25 passing the port, 83, to pass by the valve through the notches between the projections, 89. This valve and chamber are relatively dimensioned for ample clearance for the pressure fluid around the periphery of the valve, provided, as above mentioned, with the annular seating area, 88. By this construction the large area of the lower side of the disk-shaped valve, 87, is presented to the force of the pressure gases which may be delivered through the stem, 81, passing the restricted orifice, 83, thereof. Communicating 30 with the valve chamber, 86, there is a passageway, 90, which leads by way of suitable pipe connections 48 to the fuel container, A, hereinafter described, from which liquid fuel is to be fed to the engine carburetor. It will be noted that this passageway, 90, has its outlet within the inner circumference of the annular seating area,—and therefore within the annular seat—of the valve, 87, which seat is formed upon the upper wall of the valve 35 40 45 50 55 60 65 70 75 80 85 90 95 100

chamber, 86, in the housing member, 85, so that the passageway for the pressure gases from the engine to the passageway, 90, is controlled by this valve, being cut off when the 5 valve is seated by the pressure gases after a limited movement of such gases around the periphery of the valve in the clearance provided as mentioned, such movement occurring only during the delay in the seating of the valve, 10 87, after the beginning of the pressure-producing stroke of the engine piston, while the pressure is rising to the degree necessary for lifting the valve and overcoming its inertia. Positioned for encountering the center of the 15 disk valve, 87, to further delay the seating of the valve, there is provided the stem, 91, of a conical valve, 92, which seats at a port, 94, leading from the valve chamber at the side at which the valve, 87, is seated, and 20 from within the annular seat, to an atmosphere vent through ports, 99 and 100, in a spring-retaining sleeve, 97, and adjusting cap, 101, respectively, hereinafter described. The spring, 96, located within said spring- 25 retaining sleeve, 97, which sleeve is arranged to slide in a bore provided for it in the terminal nipple, 85^a, of the housing, 85, reacts between said sliding retainer and the valve, 92, for holding it normally seated against out- 30 flow of gases from the valve chamber, 86. The cap, 101, screwed onto the upper end of the part, 85, serves for retaining the retainer, 97, and for adjusting the tension of the spring by screwing said collar, 101, more 35 or less onto the threaded nipple in which said retainer, 97, slides. Said collar, 101, is provided with a notched flange, 102, whose notches are engaged by a spring arm, 103, secured to the housing, 85, by means of a 40 screw, 104, for holding the collar, 101, in adjusted position.

On one side of the housing, 85, there is provided a nipple projection, 85^a, interiorly screw-threaded and adapted to be connected 45 by a coupling device of any desired character indicated at 85^c, to the tube, 48, which is in turn connected by any suitable coupling, as 49, to the top of a container indicated as to its entirety by reference character A.

50 This container comprises a casing, 50, having at the upper end a threaded nipple, 50^a, for connection by the tube, 48, with the discharge nipple, 85^a, of the pressure-transmitting and limiting device, 80. The cavity of 55 the casing, 50, indicated by the numeral 51 is provided at the lower end with a hollow screwed-in fitting, 57, having an upwardly facing shoulder, 57^a, constituting a seat for a downwardly-seating check valve, 61, and 60 having below said valve seat a groove, 57^b, which forms a seat for a strainer, 58, which is retained by a spring ring, 59, sprung thereinto in a manner which will be understood without further explanation. The upper end of the 65 fitting, 57, is exteriorly reduced in diameter

and undercut, as seen at 57^c, for engaging check fingers, 62, which are sprung into engagement with the reduced upper end flange of the fitting, and which overhang the check valve, as seen at 62^a, for limiting its movement upward away from its seat. 70

The chamber, 51, is enlarged at its lower part to substantially twice the diameter of its upper part for accommodating at the lower end the large fuel intake with the large 75 check valve, 61, as shown. Alongside the upper unreduced portion there is formed integrally with said casing, 50, an air trap chamber, 105, substantially equal in cross section to the upper part of the chamber, 51, 80 said air trap chamber terminating with the bottom web, 105^a, a short distance above the check valve, 61. The unitary casing comprising both the chambers 51 and 105, has an encompassing flange, 112, which is extended at the plane of the web, 112^a, which is the upper limit of the enlargement of the chamber, 51. This flange, 112, affords means of securement of a jacket, 111, which encloses the lower portion of the casing, 50, forming a 85 liquid-receiving vacuum trapping chamber to which at the upper end through said web, 112^a, connection is made for delivery of liquid from the main source as indicated by the fitting, 110, screwed into said web at a 90 position laterally with respect to the air trap chamber, 105. The liquid is discharged from the container, A, and specifically from the air trap chamber, 105, by way of a discharge pipe, 108, which is inserted through the 95 upper end of the chamber, 105, terminating for intake, as seen at 108^a, at the lower part of the chamber, 105. As hereinafter more particularly described, the fuel enters the trap chamber, 105, through the port, 106, at 100 the lower end of that chamber, said port being controlled by a non return check valve, 107, which may be, as shown, a thin disk seated upon the flat bottom web of the chamber, and checked as to its movement away 105 from its seat by the near proximity of the lower intake end of the discharge tube, 108. In the chamber, 51, there is provided a float, 52, whose upper end constitutes a valve, 53, seating upwardly at a seat, 50^b, formed around the discharge port, 50^c, through the nipple, 50^a. This float is desirably diametered, or has the flange which constitutes the valve, 53, diametered, for limiting lateral movement in the chamber, 51, so that it cannot move laterally out of seating range with respect to its seat, 50^b. 110

The operation of the construction described may be understood to be as follows:

The several parts and elements being connected as shown in Figure 1, when the engine is turned over in the compression stroke of the piston, the pressure of the gases in the cylinder to which the device, 80, is connected, is communicated through said device, around 120

the valve, 86, through the passageway, 90, and connecting pipe, 48, to the chamber, 51, where the pressure thus exerted upon the liquid within the chamber, 51, operating as herein-
 5 after more particularly described, by way of the air trap chamber, 105, causes the liquid to be forced past the check valve, 107, and through the discharge tube, 108, and connecting tube, 79, to the float chamber, C, of the carburetor. The pressure thus applied to the valve, 87, causes the same to become seated entirely, on the compression stroke of the engine piston. The seating of the valve 86 by the force of the engine pressure causes the
 10 valve to engage the stem 88 of the venting valve 94 and thereby opens the valve against the force of the spring 96 normally holding the valve 94 in seated position. The pressure transmitted past the valve 86 to the fuel feeding chamber 51 before the seating of the valve 86 will thereby be vented through the opening of the valve 94 allowing atmospheric pressure to act upon the fuel in the chamber 51. If the chamber 51 is fed by gravity
 15 from the supply tank the venting of the connections in this way permits the chamber, 51, to receive a further charge of liquid fuel from the jacket, 111, which in turn is thereby caused to receive a further charge from the main fuel tank, 70, such further charge passing into the chamber, 51, past the plate check valve, 61, the check valve, 107, being seated during this filling operation. If, on
 20 the other hand, the chamber 51 is at a higher level than the level of the fuel in the supply tank, the next suction stroke of the piston produces an opening of the valve 87 permitting the venting valve 94 to seat and producing a suction in the connection 48 leading to the chamber 51 which is sufficient to cause the filling of the chamber 51 from the jacket 111. It will be obvious that the provision of the venting valve 94 prevents the drawing
 25 of an excessive amount of air into the engine cylinder during the suction stroke of the piston. The next pressure stroke of the piston will again seat the valve 87 producing delivery of the fuel from the chamber 51 prior to the opening of the venting valve 94. It will be understood that during the feeding operation described, the chamber, 51, will supply liquid to the float chamber, C, of the carburetor only until the operation of the float
 30 valve within said chamber, C, prevents the further feeding of the liquid in this way; and thereupon the accumulation of liquid within the chamber, 51, will cause the float, 52, to rise and seat the valve, 53, at the seat 50^b, thus preventing further flow of liquid derived from the main tank, 70, into the chamber, 51.

Upon considering again the structure as shown in Figure 2, it may be understood, first,
 35 that the liquid will be supplied to the con-

tainer, A, from the main tank, or main liquid source of whatever character, by gravity flow under atmospheric pressure, or whatever pressure may be operative upon the liquid in said source, automatically to the jacket, 111, from which, passing by the check valve, 61, the chamber 51, will be filled until the float, 52 seats the valve, 53; and that while in the process of filling the chamber, 51, above the level of the port, 106, of the air trap chamber, the liquid will pass by the check valve, 107, into said air trap chamber freely until the intake, 108^a, of the discharge pipe, 108, is submerged, and thereafter to the extent that the compression of the air above the liquid in the air trap chamber may be caused and measured by the head of the liquid in the chamber, 51, above the level of the intake port, 108^a, of the discharge tube, 108; and that at the same time the level of the liquid in the chamber, 109, of the jacket, 111, around the casing, 50, under some circumstances hereinafter described may rise to the full capacity of the chamber, 109.

It will be understood, therefore, that in the intervals between the pressure impulses derived from the engine, which may be referred to as the sub-atmospheric intervals, during which the container is deriving liquid supply from the main source, the supply of liquid to the carburetor, or whatever device is being served, is maintained through the discharge tube, 108, and connection pipe, 79, by the stored pressure of the air compressed in the trap chamber, 105, by the head of liquid in the chamber, 51, as mentioned.

Upon considering the construction and mode of operation indicated, it may be understood that when the structure is operating so that the chamber, 51, is maintained substantially full, the liquid in the chamber, 109, of the jacket, 111, around the casing, 50, will rise to a level at which the degree of rarefaction or compression of the trapped air will counterpoise the hydrostatic head of the liquid in the fuel pipe, 67, and tank, 70, in view of the height of the fuel in the main tank; and if the level of fuel in the main tank is above the level of the inlet to the chamber, 109, so that when the connecting pipe with its downward and upward loops is once filled with liquid, the fuel tends to flow by gravity into the chamber, 109, that chamber will be filled to a level to which the amount of air which has been trapped at sub-atmospheric pressure in the upper part of the chamber, 109, by the liquid rising to the height of the valve fitting, 57, and sealing off the upper part of the chamber, 109, from the lower sediment-collecting part, is compressed and changed from a condition of sub-atmospheric pressure produced by suction, to the condition of compression or lessened rarefaction corresponding to and counterpoising said hydrostatic head. When the conditions are such that the fuel tends to

flow by gravity from the main tank to the device, A, the suction will only tend to hasten the promptness of the response to the engine demands thereafter. But a purpose of the invention being to ensure fuel supply to the engine under all conditions of road travel, including the conditions when the vehicle is on an ascending grade causing the fuel level in the main tank located at the rear of the vehicle to be as much below the level of the intake of the chamber, 109, as it may be above that level when the vehicle is on a descending grade, the operation most important to be considered is that which obtains when the fuel is required to be lifted by suction from the main tank to the point of downward flow, as when the vehicle stands on an ascending grade, under which conditions a high degree of vacuum must be built up in the chamber, 109, in order to fill the apparatus for supplying the engine. And if later the vehicle is standing on a level or descending grade with the chamber, 51, filled to the top, the liquid level in the chamber, 109, may, as above mentioned, rise somewhat, because the air initially trapped at sub-atmospheric pressure is now condensed to atmospheric pressure,—because no suction is required for lifting the fuel,—and is therefore accommodated in less space than when it was trapped at sub-atmospheric pressure. Upon considering the operation of the structure under such conditions, it will be observed that this mode of operation is in part dependent upon the arrangement by which the fuel pipe line from the main tank discharges into the device, A, at the upper part of said device, that is at a substantial distance above the intake past the check valve, 61, into the fuel feeding chamber, 51, so that it falls from the point of entrance at the upper part of the chamber, 109, through the air trapped in the upper part of that chamber to reach and occupy and eventually fill to the level for sealing the intake past the check valve, 61, the lower sediment trapping portion of the chamber, 109.

I claim:

1. In a construction for the purpose indicated, a main source of liquid, a liquid container connected for receiving liquid by flow from the main source; a check valve preventing return flow; means for effecting changes of pressure on the liquid in said container; an air trapping chamber connected for receiving liquid from said container; a check valve preventing return flow toward the container; a liquid discharge conduit having intake at the lower part of the air trapping chamber and leading upwardly for liquid discharge, and a removable jacket extending below and around the container enclosing the same from the lower end thereof, upwardly to a level a substantial distance above the said first mentioned check valve, the connection for liquid supply from the main source

to the container being made by connection with said jacket at a level above said check valve.

2. In a construction for the purpose indicated, a main source of liquid, a liquid container connected for receiving liquid by flow from the main source; a check valve preventing return flow; means for effecting changes of pressure on the liquid in said container; an air trapping chamber connected for receiving liquid from said container; a check valve preventing return flow toward the container; a liquid discharge conduit having intake at the lower part of the air trapping chamber and leading upwardly for liquid discharge, and a chamber surrounding the container and enclosing the lower end thereof and extending upwardly to a level a substantial distance above the first mentioned check valve, the connection for liquid supply from the main source to the container being made by connection with said last mentioned chamber at a level above said check valve.

3. In a construction for the purpose indicated, a main source of liquid, a chamber connected for receiving liquid by flow from the main source; a second chamber protruding fixedly downwardly into said first mentioned chamber having check valve-controlled access at the lower end for fuel from said first chamber; means for effecting changes of pressure on the liquid in said second chamber; a third chamber extending fixedly down into said second chamber and having check valve-controlled communication at its lower part with said second chamber and upward discharge from its lower part; whereby in the intervals of flow from the first chamber into the second liquid may be accumulated in the third chamber to a height above the level of discharge from said second chamber into the third.

4. In combination with a fuel supply chamber for the carburetor of an internal combustion engine and the like, a conduit through which the engine pressure is transmitted to said fuel supply chamber; a valve chamber in said conduit; a normally open valve in said chamber adapted to be seated by the engine pressure, the valve chamber affording clearance around the valve for transmission of said pressure toward the fuel supply chamber at the normally open position of the valve; a duct leading from the valve chamber at the side of the valve opposite the engine pressure inlet to said valve chamber, said duct forming part of the engine pressure conduit to the fuel supply chamber; a duct leading to atmosphere from the side of the valve chamber at which the valve is seated by the engine pressure at the seated position of said valve, and communicating with the duct leading to the fuel supply chamber; a valve controlling said atmos-

phere inlet duct; yielding means for holding the last-mentioned valve normally seated against atmosphere inlet, and means by which the engine-pressure-operated valve 5 opens said atmosphere valve in the seating movement of said engine-pressure-operated valve.

5. In the construction defined in claim 4, the engine-pressure-operated valve being 10 normally open by gravity, the wall of the valve chamber on which said valve rests by gravity at open position and the valve at that side being co-operatively formed for affording clearance past the valve for air inflow toward the engine cylinder in the suction stroke of the engine; whereby, due to the 15 atmosphere valve being normally closed against air inflow, such inflow is derived through the conduit leading to the fuel chamber, tending to produce a vacuum in said chamber.

6. In a construction for the purpose indicated, a fitting arranged for connection with a source of alternating fluid pressure and 25 suction and also for connection with the chamber to be served with such alternating pressure and suction, said fitting having a valve chamber and a passage leading therefrom at one side thereof to the source of alternating pressure and suction, and passages leading from the other side respectively to the chamber to be served and to the atmosphere; a valve in the valve chamber dimensioned relatively thereto for short movement 30 between the opposite walls from which said passages respectively lead, and for seating to close the ports of the two passages last mentioned and for being stopped at the other side without closing the port of the first 35 mentioned passage; an outwardly opening valve controlling the atmosphere passage; a spring holding said valve normally seated, and means for adjusting the spring to regulate the pressure at which the valve will open.

7. In the construction defined in claim 6, said adjusting means comprising an apertured cap screwed onto the terminal of the fitting through which the atmosphere passage opens, adapted to stop the outer end of the 40 spring, whereby the spring may be adjusted for its valve seating pressure by screwing the cap more or less onto the fitting, and a spring catch arranged to engage the exterior margin of the cap for holding it at 45 adjusted position.

8. In the construction defined in claim 6, a housing for the spring interposed in the fitting consisting of a sleeve mounted slidingly in the fitting having its upper end closed 50 except as to an atmosphere aperture and a screwed-on adjusting cap having an aperture registering with the aperture in said sleeve.

9. In a construction for the purpose indicated, a main source of liquid, a liquid 55 container connected for receiving liquid from

the main source, a check valve preventing return flow, means for effecting changes of pressure on the liquid in said container, an air trapping chamber connected for receiving liquid from said container, a check valve preventing return flow toward the container, a liquid discharge conduit leading from the air trapping chamber for liquid discharge, and a removable jacket extending below and around the container and upwardly to a level 70 a substantial distance above the first mentioned check valve, the connection for liquid supply from the main source to the container being made by connection with said jacket at a level above said first mentioned 75 check valve.

10. In a construction for the purpose indicated, a main source of liquid, a liquid container connected for receiving liquid from the main source, a check valve preventing return flow, means for effecting changes of pressure on the liquid in said container, an air trapping chamber connected for receiving liquid from said container, a check valve preventing return flow toward the container, a liquid discharge conduit leading from the air trapping chamber for liquid discharge, and a chamber around the container at the lower end thereof and extending upwardly above the first mentioned check valve, the connection for liquid supply from the main source to the container being made by connection with said last mentioned chamber at a level above said first mentioned check 80 valve.

11. An apparatus for supplying fuel to an internal combustion engine comprising three separable casing parts, two of which are secured together and enclose a pumping chamber, the third casing part being removably secured to one of the first two casing parts to form a fuel-receiving and trapping chamber, one of said first two casing parts having an inlet communication between said chambers, a check valve controlling said inlet for flow from said fuel-receiving chamber to said pumping chamber, a filter screen mounted in junction with one of said first two casing parts and spanning the inlet communication between said chambers, an inlet 105 connection to one of said first two casing parts from a source of fuel supply and delivering into said fuel-receiving chamber antecedent to said filter screen whereby the fuel is filtered as it is drawn into the fuel 110 pumping chamber, a valve-controlled outlet passage from said pumping chamber, a flange formed integral with one of said first two casing parts for mounting the casing on the engine and an operating connection from the engine attached to the casing part having the attaching flange for producing alternate 115 conditions of suction and pressure within said pumping chamber for feeding the fuel.

12. An apparatus for supplying fuel to an 120

internal combustion engine comprising a pump casing having a fuel pumping chamber, means operated by the engine for producing changes of pressure within said pumping chamber, inlet and outlet passages communicating with said pumping chamber, valves controlling said passages for one way flow therethrough, an inlet connection directly to said pump casing from a source of fuel supply independent of the inlet and outlet passages to the pumping chamber, an outlet connection directly to said pump casing in communication with said outlet passage for delivery of fuel therefrom, a fuel-receiving and sediment trapping chamber removably secured to said pump casing independent of said connections forming a closed communication between the delivery opening of said inlet connection and said inlet passage to said pumping chamber, said inlet passage opening below the upper portion of said fuel-receiving chamber whereby, as fuel is drawn into said pumping chamber faster than it is delivered from the source of supply, vacuum is trapped in the upper portion of said fuel-receiving chamber and tends to maintain a substantially constant flow into said fuel-receiving chamber while the fuel is intermittently sucked into said pumping chamber.

13. A system for the purpose indicated comprising a fuel container having a fuel receiving chamber and a fuel feeding chamber, the fuel receiving chamber encompassing the fuel feeding chamber in sealing relation at a lower portion of the latter and extending a substantial distance below the latter and having at its upper part at a substantial distance above the level of the lower end of the fuel feeding chamber a fuel inlet, arranged for connection therefrom to a fuel source, the fuel feeding chamber having connection with means for producing alternating super-atmospheric and sub-atmospheric pressure therein and having one-way flow discharging connection from its lower part comprising a fuel discharge chamber within the fuel feeding chamber having its inlet from the latter at the lower end and having for fuel discharge from said fuel discharge chamber, a conduit opening within said fuel discharge chamber at the lower end portion thereof and extending upwardly and emerging through the upper end of said fuel discharge chamber and of the fuel feeding chamber, said fuel receiving chamber having one-way flow communication upwardly with the fuel feeding chamber at the lower end of the latter.

14. An apparatus for supplying fuel to an internal combustion engine comprising three separable casing parts, two of which are secured together and enclose a pumping chamber, the third casing part being removably secured to one of the first two casing parts to form a fuel-receiving and trapping chamber, one of said first two casing parts having an inlet communication between said chambers, a check valve controlling said inlet for flow from said fuel-receiving chamber to said pumping chamber, a filter screen mounted in junction with one of said first two casing parts and spanning the inlet communication between said chambers, an inlet connection to one of said first two casing parts from a source of fuel supply and delivering into said fuel-receiving chamber antecedent to said filter screen whereby the fuel is filtered as it is drawn into the fuel pumping chamber, a valve-controlled outlet passage from said pumping chamber, a flange formed integral with one of said first two casing parts for mounting the casing on the engine and engine-operated means for producing alternate conditions of suction and pressure within said pumping chamber for feeding the fuel.

In testimony whereof, I have hereunto set my hand at Long Island City, this 24th day of February, 1926.

EDWARD A. ROCKWELL.
